Hezel & Bevier,

Thrashing Mach.

Patented Feb 11, 1831.

Jacob Hootzel & Joseph Bevier
Letters Patent

The schedule referred to in these letters Patent and making part of the same, containing a description in the words of the said Jacob Hootzel & Joseph Bevier themselves of their improvement in the machine for threshing grain & shelling corn

To all, whom these presents shall come. Be it known that we Jacob Hootzel & Joseph Bevier, of Ithaca in the County of Tompkins, and State of New York, have invented a new and useful improvement in the machine for the threshing of wheat, rye, and all other kinds of grain and seed, and for shelling of corn; and that the following is a full and exact description of the construction and operation of the said machine as invented or improved by us. This machine is constructed by a frame of wood of the size and to the power to be applied, but a size suitable to be drawn by one horse is two feet wide and about three feet long, and about twenty inches or two feet high with a cylinder of iron or wood long enough to fill the width of the frame with bars of iron about one and a half inch wide and about three eighths of an inch thick; then bars are to be let edgewise into the cylinder about half the width of the bar and the outer edge chamfered down on one side so as to bring it to the thickness of one eighth of an inch thick, with teeth on the edge about like the teeth of a coarse hand saw; those bars to be placed on the cylinder about three inches apart round the surface of the cylinder, the size of which should be proportioned to the velocity to be given: a twelve inch cylinder should be so geared as to give about two hundred revolutions in a minute: a concave is then formed by square bars of iron about five eighths of an inch diameter or flat bars set up edgewise: the bars of the concave are either with or without teeth similar to those in the bars of the cylinder; those bars are stationary and about twelve in number, and about one fourth of an inch from

Drawing

each other, beginning about as high as the water of the flood in
and passing under the bottom of it about one third way around
near enough to hit the grain to be threshed; the cylinder being
governed by screws to raise it from or let it near the concave,
and is suspended by friction boxes which are held down by screws
so that it cannot raise or fall except by turning the screws;
an inclined box is placed on the back part of the frame, the
forward part of which comes close to the first bar of the con-
cave to conduct the grain or corn in under the cylinder; the
shaft of the cylinder extends through far enough to admit
of a small wheel made fast to apply the hand from a drum
or wheel to put the machine in motion; the grain or corn
passes between the surface of the cylinder and the concave bars.

What is claimed by this improvement is, the teeth in the
bars upon the cylinder acting upon the grain on the con-
cave of bars with or without teeth; and also the cylinder being
fixed and stationary so that it cannot raise or fall except at
pleasure.
